UNITED STATES PATENT OFFICE.

JASPER STANLEY WINGET, OF YORK, PENNSYLVANIA.

CIGAR-BUNCHING MACHINE.

1,296,724.

Specification of Letters Patent. Patented Mar. 11, 1919.

Application filed June 18, 1917. Serial No. 175,329.

To all whom it may concern:

Be it known that I, JASPER STANLEY WINGET, a citizen of the United States, residing at York, in the county of York and State of Pennsylvania, have invented certain new and useful Improvements in Cigar-Bunching Machines, of which the following is a specification, reference being had therein to the accompanying drawing.

My invention relates to improvements in cigar bunching machines, and the primary object of my invention is to provide a specific form of guard plates to hold the scrap tobacco within the apron pocket and to make them readily detachable so that the machine can be used for rolling cigar bunches composed of either scrap tobacco or long filler tobacco.

Another object of my present invention is to provide a specific form of means for yieldingly holding the bunching apron at the desired tension.

In the accompanying drawings—

Figure 1 is a perspective view showing one end of a cigar bunching machine embodying my invention.

Fig. 2 is a longitudinal vertical sectional view of Fig. 1.

Fig. 3 is a perspective view of a machine embodying my improvement, and showing a modified manner of attaching the yielding end of the apron.

Fig. 4 is a central vertical longitudinal sectional view of Fig. 3.

Fig. 5 is a transverse sectional view on the line 3—3 of Fig. 4.

Fig. 6 is a detached perspective view of the scrap attachment, showing the parts forming the same and in their separated relation.

Referring now to the drawings, 1 represents the base of my machine which is preferably made of a rectangular skeleton frame having the flange 2 extending over the top 45 of the table or bench to which my machine is applied and which holds it against horizontal movement in any direction. The side walls or bars 3 and 4, forming a part of the base, midway their length, are provided with 50 downwardly extending rigid arms 5 and 6 preferably formed integral with the bars 3 and 4. The end bars 7 and 8 of the base have connected thereto the vertically arranged upwardly curved bars or plates 9 and 10 55 which are spaced from the bars 3 and 4 hav-

ing spaces 11 between the same and the bars. The walls 3 and 4 are provided with the four inwardly extending ears 12 and 13 on each side through which pass the rods 14, rigidly carried by the lower face of the bed plate 15. 60 This bed plate is of a curved form fitting between the plates and supported by springs 16 surrounding the rods 14, and said springs have their lower ends resting upon the upper faces of the ears 12 and 13 whereby the 65 bed-plate 15 is yieldingly supported for a purpose hereinafter more fully pointed out.

I am aware that it is not new to provide a cigar bunching machine with adjustable guide plates for holding the scrap tobacco 70 within the apron pocket, but so far as I am aware my specific form of the plates whereby they are readily attachable and detachable, and readily adjustable, for use either for bunching scrap tobacco or the long filler 75 tobacco, and have them supported by a depending edge of the bed-plate is new with me.

The ends of the bed-plate 15 are turned downwardly as indicated at 17 and 18, and secured to the inner face of the downwardly turned portion 17 are the sliding arm portions 19 and 20 of the guards 21 and 22, which extend parallel with the plates 9 and 10 and are adjustably held by means of a bolt 80 23, whereby the guards can be moved to and from each other so that they come close to the belt which will be later more fully described. These guards 21, constitute what I term a "scrap attachment" by means of 85 which the machine is adapted to make all shaped scrap filler cigars, and which are adjustable in a direction transverse the machine to be adjusted against the edge of wide or narrow belts according to the length 90 of the cigar being made; and is also adapted to make barrel-shaped cigars with both ends having nothing but scrap, and which guards are detachable when the machine is not being used to make the cheap grade of scrap 95 filler cigars. The forward end of the base is provided with two upwardly extending ears 24 and 25, in which is mounted a shaft 26, upon which is wound a belt 26', and said shaft is held against rotation by means of 100 the ratchet teeth 27 carried by one end. The opposite end of the shaft on the outside of the ear 24 is provided with a coil spring 28, which bears against the nut 29 carried by 105 the shaft and normally holds the ratchet in 110

engagement so that the shaft cannot be rotated. When it is desired to lengthen or shorten the belt, the shaft 26 is moved longitudinally which disengages the ratchet teeth 5 and allows the shaft to be rotated so that the belt may be wound or unwound on the shaft to lengthen or shorten the same. The belt 26' extends rearwardly, resting upon the bed-plate 15 and passes downwardly at the 10 opposite end of the bed-plate under the rear bar of the base and is rigidly secured at 30 to the base. The belt is of a length to allow a loop 27' to be formed therein between the guards 21 and 22 to form a pocket in 15 which the tobacco is placed to roll the bunch.

When the machine is used for bunching scrap tobacco, the guard plates 21 and 22 are in the position shown in Figs. 1, 2, 5 and 6. When, however, the machine is used for 20 bunching long filler cigars, the guard plates are removed, because they would be in the way if left on the machine. With these guard plates in position the operator cannot properly handle the long filler bunch to 25 properly place it in the apron pocket without disturbing the arranged positions of the long filler pieces, when they are laid in the pocket, and especially is this true when the bunch is composed of "half and half", which means 30 half of one kind of tobacco and half of another kind of tobacco. Again the removal of these guard-plates gives more room in respect to the length of a long filler bunch.

The downwardly extending arms 5 and 6 35 have pivoted in their lower ends the plate 31 to which is rigidly secured the two upwardly extending arms 32 and 33 connected together at their upper ends by the rod 34 upon which is rotatably mounted the roller 35, and which 40 is arranged directly over the curved bed plate and travels across the same under the belt 26' and having a space between the same slightly greater than twice the thickness of the belt, whereby the belt is carried across 45 the bed-plate with the loop 27' therein and in which is the bunch as shown in dotted lines, Fig. 2 of the drawings. The upper end of the arm 33 is extended upwardly and provided with a lateral longitudinal pin 36 50 carrying the handle 36', whereby the roller 35 is moved across the bed-plate. Rigidly carried by the plate 31 is a bar 37 having a weight 37' at its outer end which, when the handle is released, rocks the plate carrying 55 the roller back across the bed-plate in a position for another operation.

In the modification shown in Figs. 5 and 6 of the drawings, mounted upon the base 1 is a frame 38 having the two upwardly extending arms 39 and 40, provided with slots 38' adapted to receive the shaft 26 on the outside of the edges of the belt whereby the frame 38 is supported upon the base and held against inward movement. The upper end 60 of the arms 39 and 40 are provided with elongated tubular housings 41 and 42 having closed ends 43. Fitting tightly in the housings are members 44 and 45 having reduced inner ends 46 passing through the closed ends of the housings. Surrounding the reduced ends of the members 44 and 45 within the housings are coiled springs 47, which normally hold the members 44 and 45 in their extended positions. The outer ends of the members 44 and 45 are rigidly connected by a rod 48 upon which is rotatably mounted the roller 49 and around which the belt 26' passes as clearly shown in Fig. 6 of the drawings. In this modification the arrangement of the spring dispenses with the spring bed-plate and the bed plate is rigidly supported upon inwardly extending ledges 50 carried by the curved plates 9 and 10, as shown in Fig. 6 of the drawings.

In operation the handle 36' is moved forward so as to bring the roller 35 forwardly adjacent the roller or shaft 26, upon which the belt is wound. The belt 26' is then depressed between the roller 35 and end of the bed-plate 15 forming the loop 27' in the belt. The plates 21 and 22 close the ends of the loop into which is placed the tobacco to form the bunch. The plates 21 and 22 being adjustable are close to the edge of the belt so that the tobacco cannot fall out of the loop. This adjustment of the plates allows different width belts being used on the machine for making different length cigars or bunches. The adjustment of the belt 26 for lengthening or shortening the same allows of the making of bunches of different diameters. After the tobacco is placed in the loop, the roller 35 through the medium of the handle is moved rearwardly forming the loop 27' around the bunch. The continued rearward movement of the roller, causes the loop to be rolled across the bed-plate 15, firmly compressing and rolling the bunch. Should there be too much tobacco in the loop, the belt is shortened and when the roller engages the bed-plate, the same would be depressed which would indicate to the operator that the bunch is too large and the roller 35 is moved back to the starting point and a portion of the tobacco is removed. In the modification shown in Figs. 5 and 6 should the bunch be too large the roller 49 will move rearwardly against the springs 47 and indicate to the operator that the bunch is too large.

The roller 35 is carried entirely across the bed-plate and the loop in this operation causes a continued rolling of the bunch, and when the end of the bed-plate is reached the loop opens up and the bunch is removed. The side wall 3 has adjustably secured thereto by means of the thumb nut 51 the stop 52, which extends inwardly in the path of travel of the arm 32 and limits the outward movement thereof. The stop as shown can be moved so as to stop the carriage at 130

different points making the filler pocket opening larger or smaller for the convenience of the operator.

From the foregoing description and disclosure, it will be observed that the bed-plate 15 is supported by the curved bars 9 and 10 and that the bed-plate is relatively much shorter than the length of the rectangular frame 2. This construction provides a space between the front end 17 of the bed-plate and the adjacent end of the rectangular frame, in which space the belt is formed into a loop to receive the tobacco, and also provides a space between the opposite or rear end 18 of the bed-plate 15 and the other end of the rectangular frame, for the purpose of providing a space for the rolled bunch to fall from the loop and be received upon an inwardly extending flange formed on the rear end of the rectangular frame 2. The first mentioned space may be aptly termed the loop bunch receiving space, and the second mentioned space may be aptly termed the bunch delivering space.

Having thus described my invention what I claim and desire to secure by Letters Patent is:

1. The combination with a cigar bunching machine comprising a bed-plate, a bunching apron co-acting therewith and adapted to form a pocket at one end of the bed-plate, the bed-plate having a depending edge adjacent the apron pocket, of guard plates adapted to be located at opposite ends of the apron pocket, each plate having an inwardly projecting arm, and means adapted to attachably and adjustably connect the arms with the depending edge of the bed-plate.

2. The combination with a cigar bunching machine comprising a bed-plate, a bunching apron co-acting therewith and adapted to have a pocket at one end of the bed-plate, the end of the bed-plate adjacent the apron pocket having a depending edge, of guard plates adapted to be located at opposite ends of the apron pocket, each plate having an inwardly projecting arm provided with a longitudinal slot, and a clamping bolt passing through the said depending edge and the slots of the arms, whereby the guard plates are readily attachable and adjustable upon the depending edge of the bed-plate for the purpose described.

3. The combination with a cigar bunching machine comprising a bed-plate having at one end a depending edge, a bunching apron co-acting with the bed-plate and adapted to have a pocket adjacent the depending edge, of guard plates adapted to be

located at opposite ends of the apron pocket, each guard plate having an inwardly extending sliding arm and a cutout portion for said depending edge, and means for attachably and adjustably connecting the said arms to the depending edge of the bed-plate, for the purpose described.

4. The combination with a cigar bunching machine having a base, a bed-plate, a belt and a roller, of a removable frame adapted to straddle the said roller, the removable frame carrying a horizontally yielding roller over which the belt passes.

5. The combination with a cigar bunching machine having a base, a bed-plate, a belt and a roller, of a removable frame adapted to straddle the said roller and rest upon the base, two cylinders carried by said frame, rods in the cylinders, springs normally holding the rods outwardly and a roller rotatably supported by the outer ends of the rods and over which the belt passes.

6. A cigar bunching machine comprising a base, a bed-plate, a belt passing over the bed-plate, a roller adapted to travel across the bed-plate and form a cigar bunch loop in the belt in rear thereof, two cylinders horizontally supported by the base and having closed inner ends, pistons in said cylinders having reduced ends extending through the closed ends of the cylinders, nuts adjustable on the reduced portions of the pistons outside of the closed ends of the cylinders, springs surrounding the reduced portions within the cylinders and normally holding the pistons outwardly, and a roller rotatably supported by the outer ends of the pistons and over which the belt passes, substantially as described.

7. The combination with a cigar bunching machine having a base, a bed-plate, the base projecting beyond the bed-plate and one end of the base having upwardly projecting ears at its corners, a transverse roller supported by said ears, a removable frame supported by the base between the said ears, the frame carrying a spring projected roller located in a plane beyond the first said roller, and a belt having one end connected with the first said roller passing around and over the spring projected roller, over the bed-plate and its opposite end connected to the opposite end of the base.

In testimony whereof I hereunto affix my signature in the presence of two witnesses.

JASPER STANLEY WINGET.
